M. TAMINI.
ROTARY PUMP.
APPLICATION FILED JUNE 23, 1920.

1,392,090.

Patented Sept. 27, 1921.

MARIO TAMINI,

Inventor:

per H. W. [Signature]

Attorney.

UNITED STATES PATENT OFFICE.

MARIO TAMINI, OF MILAN, ITALY.

ROTARY PUMP.

1,392,090.

Specification of Letters Patent. Patented Sept. 27, 1921.

Application filed June 23, 1920. Serial No. 391,126.

To all whom it may concern:

Be it known that I, MARIO TAMINI, a subject of the King of Italy, residing at Milan, in the Kingdom of Italy, have invented new 5 and useful Improvements in Rotary Pumps, of which the following is a specification.

The present invention refers to a multiple rotary centrifugal pump in which, in order to realize a more compact construction, the 10 various passages in the stationary part of the pump are arranged to cross each other, the passages being arranged in such a manner that the water flows in opposite directions in alternate passages and the delivery 15 outlet or outlets are arranged on the same side of the pump as the suction inlet.

One constructional form of the pump according to the invention is shown by way of example in the annexed drawing, in which: 20 Figure 1 is an axial section on line 1—1 of Fig. 2, and

Fig. 2 is a section through planes at right angles to the pump axis.

Into the inlet pipe —a— is inserted in 25 well known manner the pump shaft —b— on which the impeller or running portion is mounted. The impeller is double and comprises two helical blade groups —c— and —d— separated from each other by a web 30 —e— which fulfils the duty of stiffening arms, the two groups of blades with the separating web forming virtually two distinct impellers with centrifugal circulation.

The outer ends of the passages formed by 35 the helical blades within the rotors —c— and —d— deliver into a peripheral casing, to which are alternately connected sets of guiding passages —f— and —g—. The 40 passages of the two sets run in opposite directions and are formed by helical surfaces; the passages of the set —f— receive the liquid from the rotor —c— and convey it into the channels —h— of the casing by which the rotor —d— is fed, whereas the

passages of the set —g— receive the liquid 45 from the rotor —d— and convey it to the outlet or outlets —i— provided in the casing.

The priming of the pump can be effected by any known vacuum pump. 50

Having now described my invention and how the same is to be carried out, what I claim as my invention is:

1. A multiple rotary pump comprising an impeller with two groups of blades arranged 55 one on each side of a central web, a peripheral distributor comprising two sets of passages, one set leading from the outlets of the first blade group to the inlets of the second blade group, and the other set from the 60 outlets of the second blade group to the discharge, these sets of passages being so arranged that the fluid flows alternately in opposite directions in the two sets and that parts of said passages lying parallel to the 65 axis of the impeller are located at equal distances from the said axis.

2. A multiple rotary pump comprising an impeller with two groups of blades arranged one on each side of a central web, a peripheral distributor comprising two sets of passages, one set leading from the outlets of the first blade group to the inlets of the second blade group, and the other set from the outlets of the second blade group to the discharge, these sets of passages being so arranged 70 that the fluid flows alternately in opposite directions in the two sets and that parts of said passages lying parallel to the axis of the impeller are located at equal distances from the said axis, a suction pipe admitting the fluid to the inlets of the first blade group, and a collecting head chamber 75 having delivery pipes connected thereto arranged on the same side as the suction pipe. 80

In testimony whereof I affix my signature. 85

MARIO TAMINI.
